UNITED STATES PATENT OFFICE.

ARTHUR W. PALM, OF MINNEAPOLIS, MINNESOTA.

STORM-SASH HOLDER.

Application filed April 10, 1922. Serial No. 551,366.

To all whom it may concern:

Be it known that I, ARTHUR W. PALM, a subject of the King of Sweden, residing at Minneapolis, in the county of Hennepin and 5 State of Minnesota, have invented certain new and useful Improvements in Storm-Sash Holders, of which the following is a specification:

This invention relates to builder's hardware and the main object is to provide an improved, efficient and practical storm sash opener, closer and holder. Further objects will be disclosed in the course of the following specification and are illustrated in the 15 accompanying drawing, in which:

Fig. 1 is a sectional elevation through a common and well known construction of window frame and sashes, embodying my invention.

Fig. 2 is an enlarged sectional detail corresponding to the lower portion of Fig. 1, but showing the inner sash and the storm sash as closed.

Fig. 3 is a horizontal view through the 25 window sashes and frame, as seen substantially when looking down in Fig. 2.

Referring to the drawing by reference characters 3 designates a window frame, having an inclined window sill 4, parting strips 5 and stops 6 and 7, between which slide the inner and outer window sashes 8 and 9, all of common and well known construction. In a recess 10 of the frame 3 is positioned the storm sash 11, the same being 35 hung by suitable hinges, as at 12, in the customary manner.

The invention is embodied in a device which is co-operatively connected to the inner sliding sash 8 and the storm sash 11, 40 and consists, in the main, of a pair of comparatively stiff coil springs 13, which are pivotally secured at their lower ends, as at 14, to the lower bar of the inner sash 8, and are similarly secured at their upper ends 45 to the vertical rails of the storm sash, as at 15. Said lower bar of the inner sash 8, is further provided, at about its middle, with a rigid hook member 16, adapted to engage in a small bracket 17, rigidly secured on 50 the lower rail of the storm sash 11. Some sort of a latch, such as 18 (see Fig. 1), is used to lock the sliding sashes 8 and 9 together when they are closed.

When the invention has been properly 55 constructed and applied to a window con-

struction, substantially as shown in the various views of the drawing, it will be readily understood that when the inner sash 8 is raised it will cause the storm sash 11 to open to any extent desired. It will also be understood that the springs 13 are stiff enough so that they will not buckle up or bend out of shape when in a position, as for instance in Fig. 1, but will firmly retain their shapes almost as if they were solid elements. 60

Now when the inner sash is closed, it will further be obvious that the storm sash will also be drawn in and closed. But as the leverage or pull on the storm sash decreases as the springs 13 assume more vertical positions, I have arranged the connections at the ends of the springs so that the springs will be stretched out of their normal positions by the time the inner sash is fully closed. This provision will provide a greater 70 pull on the storm sash, when most needed, and will also permit the sash to be raised sufficiently to enable an instrument to be used against the storm sash to force it open when it is stuck or frozen in its recess. 80

The coil spring construction thus far described is usually adequate and sufficient for the purposes mentioned, but it is occasionally found that the storm sash will rattle from a strong wind, when closed, and to overcome this objection I have provided the hook 16 which automatically engages in the bracket 17 and positively holds the window 85 11 secure from any vibrations whatever.

It is understood that the details of this invention, as herein set forth, are subject to many modifications, provided the same come within the spirit and scope of the appended 90 claims. What I claim is:

1. In combination with a vertically slideable window sash and a storm sash adapted to be swung outwardly therefrom, coil springs connected at their upper ends to the storm sash and at their lower ends to the 95 slideable window sash.

2. In combination with a vertically slideable window sash and a storm sash adapted to be swung outwardly therefrom, a pair of normally rigid coil springs, respective means for pivotally securing the lower ends of the springs to the sliding sash and their upper ends to the storm sash. 105

In testimony whereof I affix my signature.

ARTHUR W. PALM.
